UNITED STATES PATENT OFFICE.

HENRY G. PEPINO, OF NEW YORK, N. Y.

BOTTLE-STOPPER SEAL.

Application filed October 6, 1925. Serial No. 60,849.

This invention relates to bottle stopper seals and has for an object to provide an improved construction wherein means are presented for appreciably destroying the label on a bottle before the stopper can be removed.

Another object of the invention is to provide an improved construction which will positively indicate that the bottle has been 10 opened when the stopper is removed so that a purchaser may readily tell whether or not the contents is the original.

A still further object, more specifically, is to provide a bottle with a label of usual 15 structure around the body and a covering cap structure arranged over the stopper together with a gripping wiring or ligament positioned to mutilate and destroy to a large extent the label and the cap before permitting the stopper to be removed.

In the accompanying drawing—

Figure 1 shows a bottle with an embodiment of the invention applied thereto.

Figure 2 is a sectional view through Figure 1, approximately on line 2—2.

Figure 3 is a transverse sectional view through Figure 1 on line 3—3.

Figure 4 is a transverse sectional view through Figure 1 on line 4—4.

Figure 5 is a perspective view of the bottle shown in Figure 1 before the cap and label have been applied.

Referring to the accompanying drawing by numerals, 1 indicates a bottle of any desired kind provided with a body 2 of any usual or preferred structure and a neck 3 also of any usual structure, said neck having the usual opening in which a stopper 4 is adapted to be inserted. The stopper 4 is 40 shown as cork and acts normally to prevent the contents of the bottle from spilling.

In vending or selling certain bottled matter, it is very desirable that the purchaser be reassured as to the genuine contents. The 45 present invention presents means for absolutely reassuring a customer that the original contents of the bottle is still in the bottle untampered with. This assurance is brought about by the sealing means disclosed in the 50 accompanying drawing. This sealing means includes a sealing wire, ligament or cord 5 of any desired kind, bands 6, and the usual label 7 merging into a covering cap 8. The cord, ligament or wire 5 is looped around 55 the stopper 4 and given preferably a single twist to make a partial knot 9 so that one

section or end portion 10 of the wire 5 may extend down over one side of the body 2 while the other section extends across the top of the stopper 1 and is preferably pressed 60 into the stopper somewhat so as not to readily move therefrom, said crossing section 11 merging into what may be termed the ripping section or end 12 which has a portion 13 projecting below the bottle. This 65 portion may be temporarily bent back so as to overlap the label 7 if desired when the bottle is being packed in a case. It will be noted that the straps or bands 6 normally hold the sections 10 and 12 in the position 70 shown in Figure 2. These straps or bands are preferably held to the body 2 by an adhesive and are also preferably held by an adhesive to the encircling label 7, which label may be of paper or any desired material of 75 usual construction. This label is preferably the usual labels used on bottles and may carry any desired information printed thereon. The cap 8 is really an extension of the label 7 and at the upper portion is prefer- 80 ably twisted together as shown particularly in Figure 1. If desired, adhesive may be used for holding the cap portion 8 in place. When the parts have been assembled as shown in Figures 1 and 2, the bottle is sealed 85 and no one can get access to the contents without destroying to a large extent label 7 and cap 8 as well as the bands 6.

When a person desires to remove all or part of the contents of the bottle, the ex- 90 tendsing portion 13 is grasped and pulled substantially in a direction at right angles to the height of the bottle whereupon the label 7 will be torn to a large extent as well as the bands 6, which bands assist in tearing 95 the label 7 as the wire 5 is pulled from its position against the bottle. This pulling action is continued until cap 8 has been ripped and the section 11 moved off of the stopper 4. The section 10 need not be re- 100 moved unless so desired. After the parts have been removed as just described, stopper 4 is free to be removed but in order to do the same in a convenient manner, section 5 is preferably pulled away from the bottle and 105 the stopper 4 completely removed from the encircling portion 14 of the wire 5. The contents of the bottle may then be removed or partly removed and the stopper returned for temporarily closing the same. This 110 destruction or partial destruction of the label 7, cap 8 and associated parts will al-

ways indicate to anyone that the bottle has been opened. This will prevent the bottle from being resold as an original sealed bottle and will also prevent anyone from substituting inferior ingredients.

What I claim is:

1. A bottle stopper seal, including in its construction a wire extending across the top and looped around the stopper circumferentially at the juncture of the stopper and bottle and with the ends extending from the stopper to a point adjacent to the bottom end of the bottle, and a wrapper secured to the bottle and substantially covering the same and also the stopper, said wrapper being held in place by adhesive whereby the

wrapper must be materially ripped before the stopper can be removed.

2. A bottle stopper seal, including in its construction a wire looped around the stopper circumferentially at the juncture of the stopper and bottle, with one section extending over one side of the bottle to near the bottom and the other end section extending across the top of the stopper and on the opposite side of the bottle to a point beyond the bottle, a plurality of bands secured to said bottle and clamping said ends to the bottle; said bands being spaced apart, and a wrapper secured to the bottle so as to cover the bands, wire and stopper.

HENRY G. PEPINO.
